Attorney.

UNITED STATES PATENT OFFICE.

STEPHEN T. HENNESSY, OF ST. LOUIS, MISSOURI.

WOODEN LAST.

Application filed October 27, 1922. Serial No. 597,390.

To all whom it may concern:

Be it known that I, STEPHEN T. HENNESSY, a citizen of the United States, residing in the city of St. Louis and State of Missouri, have 5 invented certain new and useful Improvements in Wooden Lasts, of which the following is a specification.

My invention relates to wooden lasts for boots and shoes, and, is a distinct and practical improvement to overcome certain practical objections to, and defects in, lasts as now universally used in shoe factories. 10 The heel portion of wooden lasts are constantly splitting, breaking down and sagging out of their normal shape due to the strain and pressure they are subjected to when used with a nailing machine and during the breasting of leather heels, and to overcome these defects in lasts, the objects 15 of my invention are, first, to provide metallic reinforcing means for the heel section of a last, which consists of a tubular core having opposed cylindrical guides each reinforced at their base with bosses anchored to 20 a metallic, preferably steel heel face plate to prevent the breaking down of the heel section of the last; second, to afford facilities for retaining the device in position in the heel portion of the last, and at the same 25 time to permit the upper end of last to be made very narrow; and, third, to provide means to indicate when reinforcing means and heel plate are in proper alignment with the tread line of the last, likewise out of 30 alignment therewith, and, fourth to provide a base of sufficient area at the base of each tubular core guide to afford strengthening means to the heel face plate to prevent it from being deformed under the most 35 severe pressure and strains, thus assuring the plate lying at all times parallel to the heel seat preventing crushing or injury to the wooden heel portion of the last and always assuring the heels to be applied to the shoes 40 in a level and proper position.

With the above and other objects in view, the invention consists in the novel features of construction, arrangement and combination of parts hereinafter more fully described and finally pointed out in the claims 45 hereto appended.

Referring to the accompanying drawings forming a part of this specification, wherein like characters of reference denote similar parts throughout the several views:

Fig. 1, is a top plan view of the heel

portion of a hinge last, showing my invention applied thereto.

Fig. 2, is a vertical sectional view thereof. 60

Fig. 3, is a bottom, or base plan view of the heel portion of a hinge last with my invention applied thereto.

Fig. 4, is a perspective view of the device embodying my features of my invention. 65

Fig. 5, is a view representing heel portion of a hinge last mounted upon a standard, the view being shown partly in section and illustrating in position, a heel and nail die, 70 or pressure means.

Referring to the drawings, the reference character 1 indicates a standard having the last supporting pin 2. 3, represents the heel portion, or section of wooden last, while 4 indicates a toe portion of the last as hinged 75 to the heel portion, as at 5.

In order to accommodate my improved heel supporting and reinforcing means, I provide the heel section 3 of the last with a central bore 6, two opposed communicating 80 bores 7, which are increased in diameter as at 8 at one end of the last heel section, said latter bores being concentric with the bores 7 and communicating with the heel surface 9 of the last section 3, as will be apparent 85 from Figures 1 and 2 of the drawings.

In carrying out the aim of my present invention, I employ a supporting and reinforcing means, which consists of a tubular post, or core 10. Integral with and disposed 90 in opposed relation are a pair of substantially cylindrically shaped guide posts 11, which guide posts extend substantially the full length of the tubular central core or post 10 and terminate at their base in a 95 boss or anvil base 12 of any desired thickness to add the desired strength to the base of the core and its guide posts. The upper ends or faces 13 of the guide posts 11 lie flush, or in a plane with the upper face 14 of the core 10, as clearly shown in Figs. 2, 4 and 6. Cast to the base of the core 10 and the bosses 12 of the guide posts 11, is a heel face plate 15 of the desired shape. This plate is relatively thin and preferably made 100 of steel, so as to hold its shape under the most severe strains and pressures during nailing and breasting operations.

The peripheral face of each guide post 11 near its upper end is provided with a plurality of serrations or corrugations 16, while the upper extremity of each guide post 11 110

is provided with an indicator projection or protuberance 17, which are preferably V shaped in plan view, as shown in Figs. 1 and 4.

5 In applying supporting and reinforcing means described to the heel section 3 of a last, the tubular core and guides are receivable in the bores 6 and 7 respectively of the wooden heel section 3 of the last, and the 10 bosses 12 are receivable in the bores or recesses 8, as shown in Figs. 1 and 2, while the heel plate 15 is brought into engagement with the heel surface 9 of the last section 3, thus covering the same and protecting its 15 surface from being defaced. The supporting and reinforcing means is preferably forced into the bore so that the serrations or corrugations 16 will frictionally hold the same from displacement, but when de- 20 sired, additional fastening means may be employed in the form of nails or screws 18 which are driven through the heel plate, as clearly shown in Fig. 3.

One end of the tubular core 10 is prefer- 25 ably plugged by means of a suitable wooden or leather plug 19 as is usual in last construction to receive a wooden peg 20 when desired, which is driven through the sole 21 and into the plug.

30 From the foregoing description, it will be apparent that the cylindrical thimble or core guide posts securely holds the thimble core or tubular post from rotary displacement, hence holding the heel plate in its 35 proper position at all times by preventing displacement thereof upon the heel surface 9 of the last section 3. It will be further observed that the gauge or indicator points 17 serve to instantly caution the operator, 40 should for any reason, displacement of the core 10 and heel plate take place under constant strains and pressure, especially after long usage of the last.

Heel sections of lasts constructed in ac- 45 cordanee with my invention will remain strong, substantial and solid, thus assuring the operator that the heel section is true or normal as to shape, which in turn retains the thimble or core in normal position to 50 permit of perfect breasting of the heel, and, retains the heel plate in normal position and shape to permit all heels to be perfectly and truly applied to shoes or boots, and, further the distance from the upper face of 55 heel section of the last to the surface of the heel plate will always remain the same. The device herein described can be depended upon to prevent breaking down of the heel portion of a wooden last, keep the hole of 60 the core or thimble in proper alignment with the last section 3, permit top of heel portion of last to be made very narrow and in general support and materially reinforce the heel portion of the last to prevent the 65 breaking down thereof, which breaking

down is a serious nuisance in the manufacture of shoes.

It will be apparent that my invention is simple and inexpensive in manufacture and in application to a last and will serve in 70 making the heel section of a wooden last highly efficient for the purpose intended.

The many advantages of the herein de- 75 scribed invention will readily suggest themselves to those skilled in the art to which it appertains.

I do not wish to be understood as having limited myself to the details of construction shown and described, but desire to have it understood that the invention I have shown 80 in the drawings is merely illustrative, as it is manifest that various minor changes may be made in the exact construction and particular arrangement of parts without departing from the spirit of my invention, hence I re- 85 serve the right to make any such changes, or modifications as may fairly fall within the scope of the appended claims when fairly construed.

What I claim is:

1. The combination, with a wooden last, 90 of a metallic plate covering the lower face of the heel section of the last, a tubular core integral with the plate and extending through the last from the lower face of the heel section thereof to the upper face there- 95 of, oppositely disposed cylindrical guide posts integral with the tubular core terminating at their free ends in a plane with the free end of the tubular core, a boss formed at the lower end of each guide post, and each of said posts each having a portion of their peripheral face serrated.

2. The combination, with a wooden last, 100 of a metallic plate covering the lower face of the heel section of the last, a tubular core integral with the plate and extending through the last from the lower face of the heel section thereof to the upper face there- 105 of and oppositely disposed cylindrical guide posts integral with the tubular core, said guide posts extending from the metallic plate and having their upper faces terminat- 110 ing in a plane with the upper surface of the core and each of said posts each having a portion of their last engaging face ser- 115 rated for locking the posts against longitudinal displacement within the heel portion of the last.

3. The combination, with a wooden last, 120 of a metallic plate covering the lower face of the heel section of the last, a tubular core integral with the plate and extending through an opening in the last from the lower face of the heel section thereof to the upper face thereof, oppositely disposed cylindrical guide posts integral with the tubular core, each of said guide posts extending 125 from the metallic plate and having their up- 130 per faces terminating in a plane with the

upper surface of the tubular core, a boss formed at the lower end of each cylindrical guide post and each of said guide posts having a serrated surface.

- 5 4. In a last structure, a wooden heel section provided with a central bore and two opposed communicating bores, said latter bores being increased in diameter at their lower end to provide shallow sockets, a tubular core receivable in the central bore, a pair of opposed guide posts integral with the tubular core receivable in the opposed communicating bores, a boss formed at the lower end of each guide post and receivable
10 in the sockets formed at the lower end of the
15

opposed communicating bores, a heel face plate integral with the lower end of the tubular core and with the bosses adapted to engage and cover the lower face of the wooden heel section, means integral with 20 the guide posts to prevent displacement of the guide posts within their respective bore and opposed means integral with the upper edges of the guide posts to indicate whether the heel face plate is in alignment with the 25 tread line of the heel section of last.

In testimony whereof, I have hereunto signed my name to the specification.

STEPHEN T. HENNESSY.
